[57] ABSTRACT

In a ramp voltage wave generating circuit, there are provided a Miller's integrator including an amplifier, a capacitor connected in parallel with the amplifier and a resistor with one terminal connected to the input side of the amplifier; a source of constant current current connected to the other terminal of the resistor; first means for maintaining at a constant value the reference potential at the output terminal of the integrator in the absence of an input signal; second means for maintaining at the constant value the reference potential in the presence of the input signal; and a three terminal active element with two terminals connected to the second means and to the source of the input signal and the remaining terminal connected to a source of reference potential.

RAMP VOLTAGE WAVE GENERATING CIRCUITS

BACKGROUND OF THE INVENTION

This invention relates to an improved circuit for generating a ramp voltage wave.

In order to have a better understanding of the invention, examples of prior art circuits will first be described. The prior circuit shown in FIG. 1 for generating a ramp voltage wave utilizes a Miller's integrator and comprises a source of input signal E_i , diodes D_1 and D_2 , a resistor R_1 connected between diode D_1 and the source E_i , an amplifier A_1 having a gain A_1 , a capacitor C_1 connected between the input and output of the amplifier, a DC source E_{b1} for providing a reference potential for determining the integrating operation at the output terminal T_2 of amplifier A_1 and a DC source E_{b2} connected to the input terminal T_1 of the amplifier.

The circuit shown in FIG. 1 operates as follows : Assuming that the input level of the amplifier A_1 in the absence of a step input from the source of input signal E_i is at zero potential, the current I_r flowing through resistor R_2 from DC source E_{b2} flows into the source of input signal E_i via diode D_1 and resistor R_1 . Denoting the terminal voltages across diodes D_1 and D_2 by E_{D1} and E_{D2} , respectively, the reference potential at the output terminal T_2 of amplifier A_1 before initiating the integrating operation will be expressed by $-E_{D1} + E_{D2} + E_{b1}$.

Upon application of the step input from the source of input signal E_i , diodes D_1 and D_2 which have been conducting are rendered OFF whereby the current I_r through resistor R_2 flows into capacitor C_1 . Thus, a ramp voltage wave of a predetermined inclination is generated at the output terminal T_2 of the amplifier A_1 following initiation of the integrating operation.

When the inclination of the ramp voltage wave is varied by varying the value of resistor R_2 or DC source E_{b2} so as to vary current I_r , flowing through resistor R_2 , such an adjustment causes the voltage E_{D1} across diode D_1 to vary so that it is impossible to maintain at a constant value the reference potential at the output terminal T_2 at instant when the ramp voltage wave begins to start.

FIG. 2 shows another prior art ramp voltage wave generating circuit designed to eliminate the defect described above, in which components identical to or functioning similarly as those shown in FIG. 1 are designated by the same reference symbols. The circuit shown in FIG. 2 comprises a comparator circuit COM including two PNP transistors TR_1 and TR_2 with their emitter electrodes coupled together. These emitter electrodes are connected to a DC bias source E_{b3} through a resistor R_3 whereas the base electrode of transistor TR_2 is connected to a source of reference potential E_c .

Comparator circuit COM corresponds to the DC source E_{b1} shown in FIG. 1. A biasing diode D_3 is connected to the collector electrode of transistor TR_2 .

With this circuit, it is possible to maintain the reference potential at the output terminal T_2 at the voltage of the source of reference potential E_c connected to the base electrode of transistor TR_2 when the ramp wave is not being provided. Assuming a voltage amplification factor of A_2 of the collector electrode of transistor TR_2 with reference to the base electrode of

transistor TR_1 it is possible to decrease to about $1/A_2$ variations in the reference potential at the output terminal which is caused by the variation in the voltage drop E_{D1} across diode D_1 when the ramp wave is initiated. With this arrangement, however, where the voltage amplification factor A_2 is increased, or where the value of capacitor C_1 is decreased for the purpose of producing a high speed ramp voltage wave, the tendency of producing an oscillation is increased thus causing unstable operation. In an integrator comprising a conventional transistor the output is about 10 volts so that the voltage drop of a silicon diode usually amounting to 0.6 volt can not be neglected. Furthermore, in the prior art Miller's integrator when the capacitor C_1 is selected to have a value of about 50 PF for producing a high speed sweeping output, the construction of the circuit shown in FIG. 2 becomes complicated.

SUMMARY OF THE INVENTION

It is an object of this invention to provide a new and improved ramp voltage wave generating circuit which can eliminate the defects of the prior art circuits.

More specific object of this invention is to provide an improved ramp voltage wave generating circuit which can maintain at a constant value the reference voltage appearing at the output terminal when the ramp voltage wave begins to start.

Another object of this invention is to provide a ramp voltage wave generating circuit having little tendency of creating an oscillation so that it is suitable for effecting high speed sweeping.

According to this invention there is provided a ramp voltage wave generating circuit comprising a Miller's integrator including an amplifier, a capacitor connected in parallel with the amplifier, and a resistor with one terminal connected to the input side of the amplifier ; a source of constant current connected to the other terminal of the resistor ; first means for maintaining at a constant value the reference potential at the output terminal of the integrator in the absence of an input signal ; second means for maintaining at the constant value the reference potential of the output terminal of the integrator in the presence of the input signal ; and a three terminal active element with two terminals connected to the second means and to the source of the input signal respectively and the remaining terminal connected to a source of reference potential.

BRIEF DESCRIPTION OF THE DRAWINGS

In the accompanying drawings :

FIGS. 1 and 2 show two examples of prior art ramp voltage wave generating circuits ;

FIG. 3 shows a connection diagram of one example of a ramp voltage wave generating circuit embodying the invention and

FIG. 4 shows a detailed connection diagram of the circuit shown in FIG. 3.

Throughout the drawings corresponding elements are designated by the same reference characters.

DESCRIPTION OF THE PREFERRED EMBODIMENT

The preferred embodiment of the invention shown in FIG. 3 comprises a Zener diode ZD corresponding to

DC source E_{b1} shown in FIG. 1, a source of constant current I_{Cs} for producing constant current output I_C , a transistor TR_3 , a diode D_4 and a source of direct current E_{b4} . Another elements are identical to those shown in FIG. 1.

In the absence of a step input from the source of input signal E_i , both diodes D_1 and D_2 and transistor TR_3 are conductive so that current flows from the source of constant current I_{Cs} to the source of input signal E_i via resistor R_2 , diode D_1 , transistor TR_3 and resistor R_1 . Further a current ($I_C - I_T$) flows from source of constant current I_{Cs} to the source of input signal E_i via transistor TR_3 and resistor R_1 . As a result, a constant current ($I_T + I_C - I_T$) = I_C always flows through transistor TR_3 independently of current I_T . Thus, the emitter voltage ED_3 of transistor TR_3 is constant so that the reference potential at the output terminal T_2 at the beginning of the ramp voltage wave is maintained at a constant value equal to $(-ED_3 + ED_2 + Eb_1)$. Upon application of a step input from the source of input signal E_i transistor TR_3 is rendered OFF whereby the current ($I_C - I_T$) flows through diode D_4 and current I_T flows through capacitor C_1 thus producing a ramp voltage wave which is determined by current I_T and capacitor C_1 .

In FIG. 4 which shows the details of the connections of the circuit shown in FIG. 3, dotted line blocks I_{Cs} and A_1 show the details of constant current source I_{Cs} and amplifier A_1 . Amplifier A_1 comprises a field effect transistor TR_6 with its drain electrode connected to source E_{b6} and a NPN type transistor TR_7 with its emitter electrode grounded. The source electrode of field effect transistor TR_6 and the base electrode of transistor TR_7 are interconnected through a base resistor R_6 . The base electrode of transistor TR_7 is also connected to a source E_{b7} through a resistor R_7 .

The constant current source I_{Cs} comprises a PNP type transistor TR_4 , a NPN type transistor TR_5 , sources E_{b8} and E_{b9} connected to the base electrodes of transistors TR_4 and TR_5 , respectively, and a resistor R_4 connected between the emitter electrode of transistor TR_4 and a DC source E_{b5} . The anode electrode of Zener diode ZD is connected to a biasing diode D_5 and a resistor R_5 which is connected to a source E_{b7} . The output terminal of amplifier A_1 is connected to a source E_{b10} through a resistor R_8 . Of course, the circuit shown in FIG. 4 operates in the same manner as that shown in FIG. 3. Where the transistors used in the circuit of FIG. 4 are of the silicon type, the emitter-base voltage of PNP type transistor TR_4 and the emitter-base voltage of NPN type transistors are equal to about 0.6 volt, respectively, so that current I_C flowing through resistor R_4 and transistor TR_3 is expressed by $I_C = [E_{b5} - (E_{b8} +$

$0.6)/R_4$ whereas current I_T flowing through resistor R_2 by $I_T = [(E_{b9} - 0.6) + E_4/R_2]$, where E_4 represents the gate voltage of the field effect transistor TR_6 .

As above described with the novel ramp voltage wave generating circuit it is possible to maintain at a precisely constant value the reference potential appearing at the output terminal T_2 at the commencement of the ramp voltage wave. Moreover as the circuit has little tendency for creating oscillation, the novel circuit is suitable for high speed sweeping so that it is applicable with good results to a high speed sweeping circuit of an oscilloscope or a delay circuit utilizing the ramp voltage wave.

While the invention has been shown and described in terms of a preferred embodiment it is to be understood that many changes and modifications may be made without departing from the true spirit and scope of the invention as defined in the appended claims.

What is claimed is:

1. A ramp voltage wave generating circuit comprising a Miller's integrator including an amplifier, a capacitor connected in parallel with said amplifier, and a resistor having one terminal connected to the input side of said amplifier; a source of constant current connected to the other terminal of said resistor; means for maintaining at a constant value the reference potential at the output terminal of said integrator in the absence of an input signal and for providing a ramp voltage at the output terminal of said integrator in the presence of said input signal; said means including a three terminal switching element with a terminal connected to said output terminal and to the source of said input signal, with another terminal connected to said constant current source and with the remaining terminal connected to a source of reference potential, said switching element being responsive to the absence of an input signal to pass a constant current from said constant current source, through said switching element to said input signal source to provide a constant voltage at said output terminal, said switching transistor being responsive to an input signal to cause a current to flow to said capacitor to produce a ramp voltage.

2. The ramp voltage wave generating circuit according to claim 1 wherein said three terminal switching element is a transistor.

3. The ramp voltage wave generating circuit according to claim 2 wherein the emitter electrode of said transistor is connected to said output terminal via a Zener diode and a diode and also to said source of input signal and the collector electrode of said transistor is connected to said source of constant current and also to said input terminal of said amplifier via another diode.
